UNITED STATES PATENT OFFICE

158,521

NEWSPAPER RECEPTACLE

Norman C. Slaughter, Rochelle, Ill.

Application March 29, 1949, Serial No. 1,684

Term of patent 14 years

(Cl. D74—9)

To all whom it may concern:

Be it known that I, Norman C. Slaughter, a citizen of the United States, residing at Rochelle, in the county of Ogle and State of Illinois, have invented a new, original, and ornamental Design for a Newspaper Receptacle, of which the following is a specification, reference being had to the accompanying drawing, forming part thereof.

In the drawing:

Fig. 1 is a front elevational view of a newspaper receptacle, showing my new design;

Fig. 2 is an end elevational view thereof;

Fig. 3 is a rear view of the upper portion of Fig. 1, showing the card holding portion of my design; and

Fig. 4 is a sectional view taken along the line 4—4 of Figs. 1 and 3.

I claim:

The ornamental design for a newspaper receptacle, substantially as shown.

NORMAN C. SLAUGHTER.
